UNITED STATES PATENT OFFICE.

CHARLES W. ASMAN, OF KNOXVILLE, TENNESSEE, ASSIGNOR TO DRAPER COMPANY,
OF HOPEDALE, MASSACHUSETTS, A CORPORATION OF MAINE.

FEELER STOP-MOTION.

1,103,340.

Specification of Letters Patent.

Patented July 14, 1914.

Application filed January 16, 1914. Serial No. 812,565.

To all whom it may concern:

Be it known that I, CHARLES W. ASMAN, a citizen of the United States, and resident of Knoxville, county of Knox, State of Tennessee, have invented an Improvement in Feeler Stop-Motions, of which the following description, in connection with the accompanying drawing, is a specification, like characters on the drawing representing like parts.

This invention has for its object to provide for automatically stopping an automatic filling replenishing loom upon the failure of the filling replenishing means to effect a transfer after the indication of substantial exhaustion of the filling in the running shuttle.

In an automatic filling replenishing loom, such, for example, as the well known Northrop type of loom, the supply of fresh filling carriers is mounted at one side of the loom and feeler mechanism is provided usually at the other side of the loom actuated upon the exhaustion of the filling in the running shuttle to a predetermined degree. Upon the actuation of the feeler mechanism the transfer mechanism is set into operation to transfer a fresh filling carrier to the lay when the filling carrier to be abandoned reaches the position for transfer. In the Northrop type of loom the filling carrier takes the form of the usual bobbin and the fresh bobbin is transferred to the shuttle knocking out the exhausted bobbin when the shuttle after indication of filling exhaustion has been boxed beneath the hopper containing the supply of fresh bobbins.

It not infrequently happens that after substantial exhaustion of the filling in the running shuttle has been indicated by the feeler, and the parts are set for transfer and a transfer of a fresh filling carrier to the shuttle should be made, that the shuttle is not properly boxed at the transfer side of the loom, and, consequently, through the action of some safety device such as the usual shuttle feeler the transferring mechanism is prevented from effecting a transfer and the shuttle is picked back to the opposite side of the loom. The feeler mechanism again detecting substantial or complete exhaustion of the filling in the running shuttle will again set in operation the transfer mecha-

nism and the operation will be repeated so long as the shuttle continues to be improperly boxed in position for transfer, resulting, of course, in the laying of a loose end in the shed which will usually be sufficient to prevent detection of filling absence by the usual weft fork. Thus, imperfect cloth will result requiring the picking out of the faulty portion before the loom can be restarted with the consequent loss of time.

This invention provides means which will automatically stop the loom upon the failure of the filling replenishing means to effect a transfer, and, in the preferred form of the invention, as it is particularly adapted to take care of the failure to effect a transfer because of an improperly boxed shuttle, the means for stopping the loom is actuated upon a subsequent presentation to the detecting means of the filling carrier, the complete or partial exhaustion of which has once been detected thereby.

The nature of the invention will appear more fully from the accompanying description and drawings and will be particularly pointed out in the claims.

The drawings show a loom of the Northrop type such as is illustrated, for example, in the patent to Wood and Northrop No. 789,472 granted May 9, 1905, with parts adapted for that type of loom and embodying the invention herein attached thereto.

In the drawings, Figure 1 is a top plan view of the loom broken away centrally and with only so much thereof illustrated as is necessary to a disclosure of the present invention; Fig. 2 is an enlarged plan view of the left hand or feeler indicating side of the loom showing the parts particularly concerned with the invention; Fig. 3 is a view in transverse cross-section of the breast beam and connected parts adjacent the latch and vibrating actuator; Fig. 4 is a view similar to Fig. 3 showing the parts in a different position; Fig. 5 is a view from the opposite side of a portion of the parts shown in Figs. 3 and 4.

The loom which is herein illustrated in connection with this embodiment of the invention is of such a familiar type and is so fully illustrated and described in the patent to Wood and Northrop mentioned that any detailed description thereof is unnecessary.

to an understanding of the present invention.

The lay is shown at 1, the breast beam at 2, the shuttle boxes at 3 and 4 at the opposite sides of the loom. The shuttle 5 is shown boxed at the left hand or feeling side of the loom. The hopper or feeder 6 is mounted on the breast beam at the right hand side of the loom carrying a supply of filled bobbins or filling carriers 7 which at the proper time are automatically transferred to the shuttle boxed at the right hand side of the loom by the mechanism such as illustrated which will be briefly described because it is made use of in the present embodiment of the invention.

A stand 8 is mounted at the left hand end of the breast beam of the loom and carries thereon a movable carrier 9 yieldingly offset toward the lay. This carrier is provided with an adjustable bunter 10 adapted to contact with the side wall of the shuttle, and also supporting a feeler 11 adapted to enter the wall of the shuttle and contact with the filling. An actuator 12 is pivotally mounted on the carrier and engages the feeler 11. So long as the filling has not become exhausted to the required extent the feeler will be limited in its movement thereby and at each beat-up will raise the free or forward end of the actuator, but when the diminution in diameter of the filling permits the feeler to extend so far into the shuttle that there can be no filling induced movement of the feeler, the actuator will not be raised, and as the carrier is moved back by the contact of the bunter 10 with the wall of the shuttle will strike against a lever 13 pivoted at 14, and known as the controller. The controller 13 will then be swung forwardly riding in the cam slot 15 of a transmitter lever 16 transversely fulcrumed or pivoted at 17. This will cause the cam slotted end of the transmitter to move downwardly and the opposite end 18 to move upwardly. The transmitter lever extends beneath, or as shown, into a slot 19 in a latch 20, rigidly secured to the controlling rock shaft 21 and overhanging the breast beam. The outer end of the latch 20 is normally out of the path of a vibrating actuator such as the weft hammer 22, but when the latch is raised by the transmitter it is brought into the path of the vibrating actuator 22, and is swung forwardly rocking the controller rock shaft 21. This shaft extends along to the transfer side of the loom, and when rocked raises a dog connected with the pivoted transferrer 23 into the path of a bunter 24 on the lay so as to cause the operation of the transferrer when the lay beats up, all in the usual manner. The controller rock shaft also when rocked brings into operative position a shuttle feeler 24 which when the lay

beats up feels for the shuttle at the transfer end of the loom, and if it is improperly boxed prevents the operation of the transferrer or of the filling replenishing mechanism. The construction and operation of the shuttle feeler is not specifically involved in this invention and may be of any well known character, such for example, as shown in the patent to C. H. Draper, No. 683,423, granted September 24, 1901.

Stopping of the loom is effected by the usual shipper 25, shown in Figs. 1 and 2, held by the notched plate 26 in running position, but which when pushed or swung rearwardly will be automatically thrown to the left stopping the loom in the usual and familiar manner. The automatic stopping of the loom is effected upon failure or absence of filling in the shed opposite and by a weft fork 27 which upon the occurrence of such failure or absence of the filling acts in a familiar manner to swing the knock-off lever 28 about its pivot 29 to release the shipper 25, and thus stop the loom.

The mechanism thus far described is all well known and familiar, and is only sufficiently illustrated herein to make clear the construction and operation of the particular embodiment disclosed herein as a preferred form of the invention.

The mechanism which when added to that already described presents a preferred embodiment of the present invention, and secures in a preferred manner the results already set forth will now be described.

A hook member is so mounted as to move backward and forward with the latch and to have an up and down movement with respect thereto. This is secured in the form illustrated by mounting rigidly upon the controller rock shaft 21 an upright arm 30 and pivoting thereto at 31 the hook member 32 which extends parallel with the latch 20 and is provided at its rearward end with a hook adapted to catch on the rear edge of the knock-off lever 28. The hook member 32 is provided above the knock-off lever with a pivoted stud 33 upon which is pivoted a spiral cam 34 and a ratchet wheel 35 integral or rigid with the cam. The ratchet wheel is mutilated lacking one or two teeth as illustrated. A pawl mechanism is carried by the hook member for co-operating with and rotating the ratchet and its attached cam. This pawl mechanism as shown comprises a pawl carrier lever 36 fulcrumed on the hook member and provided at its upper end with a pawl 37 engaging the ratchet. The compression coil spring 38 attached to the lower end of the lever 36 and to the forward end of the hook member serves to maintain the pawl normally retracted.

A pawl actuator shown as a rod 39 is

pivoted to the lower end of the lever 36, extends rearwardly substantially parallel with the latch 20 and is provided with an adjustable abutment 40 mounted thereon. A stop pin 41 on the hook member limits the rearward movement of the pawl under the influence of the spring 38. It will thus be seen that when the pawl actuator is moved forwardly the pawl will be given its actuating movement. This movement of the actuator is secured in the construction illustrated from the vibrating actuator or weft hammer 22, which for that purpose is provided with an arm 42 extended upwardly and embracing the rod 39 so as to support the rearward end of the rod, and, when the weft hammer is carried forwardly, to contact with the abutment 40 and move the pawl actuator forwardly.

20 A leaf spring 43 is secured to the side of the hook member 32 and bears at its free end against the spiral cam 34, thus serving as a detent.

The operation of the mechanism will now be apparent. The parts are normally in the position shown in Figs. 4 and 5 with the high part of the spiral cam 34 resting on the knock-off lever 28, thus holding the hook member 32 out of engagement therewith. 25 In this position the pawl is on the mutilated part of the ratchet so that as the arm 42 carried by the weft hammer strikes the abutment 40 moving the pawl actuator there is no movement of the ratchet, and the parts remain in the position illustrated. When, however, the filling carrier, such as the bobbin in the shuttle, has reached such a degree of exhaustion as to prevent a filling induced movement of the feeler and consequently, 30 through the connections already described, to cause the latch 20 to be raised into the path of the weft hammer 22, then the controller rock shaft 21 will be rocked carrying with it the arm 30 and hook member 32. 35 As these parts are swung forwardly the flat part of the spiral cam 34 will drop against the edge of the knock-off lever 28, thus allowing the hook member as the parts move backwardly to drop down and catch over 40 the opposite edge of the knock-off lever, the spiral cam being slightly rotated to bring the pawl out of the mutilated portion of the latch onto the toothed portion, and the parts thereupon take the position shown in 45 Fig. 3 of the drawings. If the transfer of a fresh filling carrier takes place in the usual manner, and there is no further indication of filling exhaustion or replenishment the arm 42 striking against the abutment 50 40 at each beat-up of the lay will cause the pawl 37 to ratchet the spiral cam 34 substantially one revolution, thus restoring the cam to the position shown in Figs. 3 and 4, and raising the hook member 32 from en-

gagement with the knock-off lever. If, however, there is instead a succeeding indication of filling exhaustion or replenishment, then the latch 20 being brought again into the path of the weft hammer will again be swung forwardly, and this time, the hook member 32 being in engagement with the knock-off lever 28, will carry forward with it the knock-off lever, thus stopping the loom.

Having fully described my invention, 75 what I claim as new and desire to secure by Letters Patent is:

1. In an automatic filling replenishing loom, loom stopping mechanism, a controller rock shaft, a vibrating actuator, a latch 80 mounted on the controller rock shaft and normally out of the path of said actuator, a filling feeler and connections to said latch to place the latch in the path of said actuator upon the detection by the feeler of the 85 required exhaustion of the filling, an arm mounted on the controller rock shaft, a hook member pivoted on said arm, a spiral cam journaled on said hook, a lever connected to the loom stopping mechanism and extended 90 beneath said cam whereby the cam normally holds the said hook out of engagement with said lever, a mutilated ratchet connected to said spiral cam, a pawl coöperating with said ratchet mounted on said hook member, 95 operative connections between said pawl and said vibrating actuator whereby upon the detection of the required filling exhaustion the spiral cam will be dropped into engagement with the knock-off lever, the pawl will 100 be caused to engage the ratchet and the hook member will be dropped into engagement with the knock-off lever to cause the stopping of the loom upon a successive detection of filling exhaustion. 105

2. In an automatic filling replenishing loom, loom stopping mechanism, a vibrating actuator, a latch normally out of the path of said actuator but which when brought into the path thereof acts to control the 110 filling replenishment, a filling feeler and connections to said latch to place the latch in the path of said actuator upon the detection by the feeler of the required exhaustion of the filling, a hook member mounted to 115 move with the latch and pivoted to move with respect to the latch, a spiral cam journaled on said hook member above a part of the loom stopping mechanism whereby the cam normally holds the said hook member 120 out of engagement with said part, a mutilated ratchet connected to said spiral cam, a pawl coöperating with said ratchet mounted on said hook member, operative connections between said pawl and said vibrating 125 actuator, whereby upon the detection of the required filling exhaustion the spiral cam will be dropped into engagement with the

part of the loom stopping mechanism, the pawl will be caused to engage the ratchet, and the hook member will be dropped into engagement with the part of the loom stopping mechanism to cause the stopping of the loom upon a successive detection of filling exhaustion.

In testimony whereof, I have signed my name to this specification, in the presence of two subscribing witnesses.

CHARLES W. ASMAN.
